(57) **CLAIM**

The ornamental design for an outdoor equipment float, as shown and described.

DESCRIPTION

FIG. 1 is a perspective view of an outdoor equipment float; FIG. 2 is a right side view of the outdoor equipment float of FIG. 1, it being understood that the left side view is identical to the right side view; and,

FIG. 3 is a top plan view of the outdoor equipment float of FIG. 1, it being understood that the bottom plan view is identical to the top plan view.
